UNITED STATES PATENT OFFICE.

JACOB MUTCHLER, OF THREE OAKS, MICHIGAN.

THILL-CO尤LING.

SPECIFICATION forming part of Letters Patent No. 351,882, dated November 2, 1886,

Application filed March 30, 1886. Serial No. 197,173. (No model.)

To all whom it may concern:

Be it known that I, JACOB MUTCHLER, a citizen of the United States, residing at Three Oaks, county of Berrien, State of Michigan, have invented a new and useful Thill and Pole Coupling, of which the following is a specification.

This invention has for its object certain improvements below described and claimed.

10 In the drawings forming a part of this specification, Figure 1 is a side elevation with vehicle-axle in cross-section; Fig. 2, top view of the coupling-bracket enlarged from Fig. 1; Fig. 3, perspective of thill-iron; Fig. 4, section on dotted line 2 2 in Fig. 2, and Fig. 5 is a cross section of the head of the thill-iron on line 1 1 in Fig. 3.

Referring to the letters of reference marked on the drawings, D is the bracket secured to 20 the axle A by clip r in the ordinary manner. The T-head c of the thill-iron P has a gain, a', on each side, making a portion of it, a little distance from the end, thinner and square-sided, instead of round, like the rest of the T-head, Figs. 3 and 5. On one side of the other end of the T-head is a little bud, t. The bracket D is chambered out, and open on top and in front in the ordinary manner. Through each side wall of the bracket is a hole 25 to receive the ends of the T-head. On one side is a slot, a, cut down through the wall into the hole. This slot is narrower than the diameter of the hole, and of width to receive the square portion of the T-head c. The other 30 wall of the bracket is provided on the inside with a guide-channel, c', down which the end of the T-head passes in coupling. The hole in this wall has a communicating recess, i, Fig. 4, to allow the bud t to pass through.

R is a rubber cushion in the back of the 40 bracket-chamber, to compensate for the wear of the T-head.

In the operation, the thills or pole, the coupling being equally applicable to either, are held at an upright angle with the T-heads 45 resting on the brackets, which supports the weight of the thills until guided to enter the slot and channel. The part between a' a', when in right position, passes down slot a, and the end of the T-head passes down the channel c' until 50 the T-head is at the holes in the bracket-walls. The thills are then moved laterally, the bud t guiding the T-head by passing through the recess i till the T-head is in place, when the thills are swung down. In their used position the T-heads have the ordinary round 55 surface in the holes of the brackets, where the wear comes.

Having thus described my invention, what I claim is—

In a thill-coupling consisting of the T-head having the mortised portion, and the bracket having the slot leading down into one of the bracket-holes, the combination of the T-head provided with the guide-bud, and the bracket 65 having the guide-channel on the inner face of the wall opposite the slotted wall, the other bracket-hole having a communicating recess through which the guide-bud passes, substantially as set forth.

In testimony of the foregoing I have hereunto subscribed my name in presence of two witnesses.

JACOB MUTCHLER.
